RAYMOND C. HAISS, OF NEW YORK, N. Y., ASSIGNOR TO GEORGE HAISS MANUFACTURING CO. INC., OF NEW YORK, N. Y., A CORPORATION OF NEW YORK.

WAGON LOADER.

Application filed October 30, 1926. Serial No. 145,142.

This invention relates to wagon loaders of the type employing an endless elevator, into the path of which the material to be loaded is moved by rotary digging elements 5 which are supported slightly above the surface of the ground over which the loader moves as it is propelled into the pile of material to be loaded.

When wagon loaders of the class mentioned are operated over rough ground or paved streets, it is desirable to maintain the digging elements so elevated that they will not be injured by striking the ground or pavement. As a result of this necessitated 10 elevation of the digging elements, more or less material may be passed over and left in the path of the loader as it progresses into the pile of material to be loaded.

An object of the invention is to provide 20 a simple, efficient and properly supported clean-up scraper, cooperating with the digging elements and projecting slightly below the same so as to collect such material as is passed over by the digging elements and 25 hold it in a position to be later acted upon by the digging elements and moved into the path of the elevator.

Other objects and advantages of the invention will become apparent from the following description taken in connection with the accompanying drawings in which: Figure 1 is a side elevation of a wagon loader with the clean up scraper attached thereto; Figure 2 is a fragmentary rear elevation of 35 the loader as seen from the left in Figure 1; and Figure 3 is a perspective view of the clean-up scraper.

The wagon loader, herein shown, includes 40 traction mechanism 5, of the endless-track type, upon which is mounted a frame 6, carrying a pair of supports 7 to which is pivotally connected an endless elevator 10, adapted to be moved, from its full line position, shown in Figure 1, to its dot-and-dash 45 line position, shown therein, through the instrumentality of a suitable raising device which includes a plurality of links *a* and *b*, pivotally connected to each other, the former of which is pivoted to the frame 6, and the 50 latter of which is secured to a shaft *c* journaled in the elevator 10 and adapted to be rotated through a suitable manually operated means, such as a worm and worm wheel not shown. By rotating the shaft *c* in one 55 direction, the links *a* and *b* are extended, as

shown in dot-and-dash lines in Figure 1, thus raising the elevator 10, and by rotating the shaft *c* in an opposite direction, the links *a* and *b* are moved to their respective full-line position, thereby lowering the elevator 60 to its full-line position. During the operation of the loader, the elevator 10 is positioned as shown in full lines in Figure 1, but when it is desired to transport the loader from place to place, the elevator is moved 65 about its point of connection with the support 7 to the position indicated by dot-and-dash lines.

The elevator 10 includes a pair of sprocket chains 11, to which are connected a plurality of buckets 12, adapted to receive the material to be loaded and carry it to the upper end of the elevator, at which point it is dumped into a chute 13, from which it passes into a suitable loading hopper 14, 70 supported upon the frame 6 in a position to deliver its contents to a wagon, truck or other vehicle. The sprocket chains 11 pass respectively over a pair of sprockets (not shown), carried by a shaft 19, suitably journaled in the upper end of the elevator, and sprockets 17 which are carried by an elongated transverse shaft 20, suitably journaled in the lower end of the elevator 10. The shaft 20 is provided with radially disposed 75 digging elements 22, the digging elements at one side of the elevator having their faces oppositely inclined to the faces of the digging elements at the other side of the elevator, so that as the wagon loader is propelled into the material to be loaded, such material is moved from both sides of the elevator toward the center line thereof and 80 into the path of the elevator to be there collected by the buckets 12. The shaft 20 is 85 rotated in the direction of the arrow A shown in Figure 1, so that the digging elements 22 impart to the material a succession of upwardly directed impacts, as a result of which the material is moved slightly forward, with respect to the travel of the loader, as well as from both sides of the elevator toward the path of travel thereof, 90 as above explained.

The shaft 19 carries a sprocket 24 which 95 is driven from a sprocket 25 by a sprocket chain 26. The sprocket 25 is mounted on and connected to a shaft 28, carrying a sprocket 29 which is connected by a sprocket chain 30 to a suitable motor 31, supported

by the frame 6. The motor 31, which is adapted to operate the elevator 10 and thereby rotate the shaft 20 with its digging elements 22 in the direction of the arrow A 5 shown in Figure 1, is also adapted for operative connection with the traction mechanism 5, through suitable gearing not shown, so that the wagon loader may be slowly moved into the pile of material to be loaded during 10 operation of the elevator 10, as well as transported at faster speeds from place to place when the elevator is positioned as shown in dotted lines in Figure 1.

When the digging elements 22 are operating in a spaced relation to a pavement or other hard surface, a relatively small amount of material is passed over by the digging elements, especially when the material to be loaded is relatively fine. According to the 15 present invention, for collecting this material, the scraper 32 is provided at the rear of the digging elements 22 preferably in such a position that its lower edge projects a slight distance below the digging elements. 20 This scraper 32 is of a length substantially equal to the length of the shaft 20, and is formed at its lower edge with an angular portion 33, which is re-enforced against bending by an angle iron 34, suitably secured 25 thereto. The scraper 32 is cut away intermediate its ends, thus providing an opening 36, adapted to accommodate the lower end of the elevator 10, the marginal portions of the scraper adjacent the opening 36 being 30 provided with angle irons 37, suitably connected thereto. To these angle irons are connected arms 38, provided at their upper ends with openings 39, adapted for the reception of bolts 40, which serve to pivotally 35 connect the scraper 32 to the lower end of the elevator 10 in a depending position, as shown in Figure 1, with the angular portion 33 of the scraper positioned at or relatively 40 near the surface of the ground over which the loader travels as it moves into the pile of material to be loaded. In order to brace the scraper 32, and thus prevent undue movement of the same as it collects the material which has not been moved into the path of 45 the elevator, a pair of links 41 are provided. These links may be of angle iron construction, and are at their rear ends pivotally connected to a transverse shaft 42, suitably supported upon the traction mechanism 5. 50 These links 41 are adapted to be detachably connected to the scraper 32 by means of pins 43, passing through the forward ends of the links 41 and the upstanding flanges of suitable brackets 44, between which the forward 55 ends of the links 41 are adapted to fit.

In order to permit the elevator 10 to be moved to its extreme position, indicated in dotted lines in Figure 1, the links 41 may be disconnected from the brackets 44 by removing the pins 43, after which the links 41

may be moved about their pivotal connection with the traction mechanism 5 to their dotted line positions shown in Figure 1, in which positions they are supported by means of lugs 48 carried by the traction mechanism 5. 70 Although it is necessary to detach the links 41 from the scraper 32 to permit the elevator 10 to be moved to its extreme position, indicated in dotted lines in Figure 1, the links 41 are of sufficient length to permit any degree of adjustment of the elevator that may be required under ordinary operating conditions. In order to prevent accidental misplacement of the pins 43, when disconnecting the links 41 from the scraper 32 to permit the elevator 10 to be moved to its horizontal position indicated in Figure 1, the pins 43 75 may be carried by chains 49 which are riveted or otherwise secured to the scraper 32, as shown at 50, one end of each chain 80 being connected to a cotter pin 51, which, when the pins are inserted as shown in Figure 3, serve to prevent their being dislodged, thereby always insuring a proper connection between the links 41 and the scraper 32 when 85 the wagon loader is in operation.

Having thus described the invention, what is claimed is:

1. In a wagon loader, a frame, an adjustable elevator, a scraper pivotally hung to 95 said elevator and adapted to move therewith upon adjustment of said elevator, and a pair of links pivotally connected to said scraper and pivotally connected to said frame whereby the scraper is carried forward as 100 the wagon loader is moved into the pile of material and whereby adjustment of the elevator is permitted.

2. In a wagon loader, a frame, an inclined elevator adapted to be moved to an inoperative position, a plurality of digging elements carried at the lower end of the elevator for moving the material to be loaded into the path of the elevator, a scraper pivotally connected to and depending from said elevator at the rear of said digging elements, and a pair of links pivotally connected to said scraper and pivotally connected to said frame, whereby displacement of the scraper with respect to the digging elements is prevented as the loader is moved into the pile of material to be loaded and whereby vertical adjustment of the scraper is permitted as said elevator is moved toward its inoperative position. 115

3. In a wagon loader, a frame, an inclined elevator adapted to be moved on a horizontal axis to an inoperative position and having a plurality of digging elements adapted to move the material into the elevator as the loader is moved into the pile of material to be loaded, a scraper at the rear of said digging elements, a pair of arms pivotally connected to said elevator and rigidly connected to said scraper whereby said scraper 125

is supported in a depending position with respect to said elevator, and a pair of links pivotally connected to said frame and adapted for detachable pivotal connection to said

5 scraper.

4. In a wagon loader, a frame, an inclined elevator adapted to be moved to an inoperative position and provided with a plurality of digging elements adapted to move the

10 material to be loaded into the elevator as the loader is moved into the pile of material to be loaded, a scraper pivotally connected to

said elevator and adapted to freely swing therefrom when the elevator is in its inoperative position, and a pair of links pivotally connected to said frame and adapted to be connected to said scraper when said elevator is in its inclined position whereby the scraper is restrained against swinging movement as the loader is moved into a pile of material to be loaded.

In testimony whereof, I have affixed my signature to this specification.

RAYMOND C. HAISS.
